UNITED STATES PATENT OFFICE.

FRANCIS W. DRAPER, OF RICHMOND, INDIANA, ASSIGNOR TO STARR PIANO COMPANY, OF RICHMOND, INDIANA, A CORPORATION OF INDIANA.

ACCENTING DEVICE FOR AUTOMATIC PLAYERS FOR INSTRUMENTS.

No. 876,442.

Specification of Letters Patent.

Patented Jan. 14, 1908.

Application filed July 18, 1907. Serial No. 384,322.

To all whom it may concern:

Be it known that I, FRANCIS W. DRAPER, a citizen of the United States, residing at Richmond, in the county of Wayne and State 5 of Indiana, have invented certain new and useful Improvements in Accenting Devices for Automatic Players for Instruments, of which the following is a specification.

The object of my invention is to produce 10 an efficient means which, operated in connection with a suitable perforated music sheet, will be capable of emphasizing particularly selected notes in order to produce solo effects.

15 The accompanying drawings illustrate only my improved apparatus, the actual note-producing mechanisms being entirely omitted for the reason that the particular style of the primary, secondary and power- 20 pneumatics (any, or all) is immaterial to the operation of my device, the structure being applicable to many types of mechanisms now common for operation directly upon the sound-producing device.

25 Figure 1 is a perspective detail, in both horizontal and vertical section, of my improved solo box, full size; Fig. 2, a sectional detail at right angles to the vertical section of the same parts in Fig. 1; Fig. 3, a dia- 30 grammatic view showing the application of my improved solo box in an ordinary "di- vided tracker board" instrument, and Fig. 4, a sectional detail of the pressure governor.

In the drawings, 10 indicates a main casing 35 divided centrally by a partition 11 into a main suction chamber 12 and a regulated suction chamber 13. The structure illustrated is especially designed for a suction system and, therefore, leading into chamber 40 13 are passages 14 which communicate with the wind chest of the operating pneumatics, and leading from chamber 12 is a passage 15 which leads to the ordinary bellows or other mechanism for producing the difference in 45 pressure to accomplish the operation of the pneumatics. Formed through partition 11 is a passage 16 which forms a direct communication between chambers 12 and 13 and, when open, a direct and ungoverned 50 communication between the wind chest and the bellows. In order to close passage 16 I provide a valve 17, which valve is normally held away from its seat, so as to leave passage 16 open, by a light spring 18 which bears

against the stem 17' of the valve. In order 55 to close this valve manually I provide a lever 19 carried by a rock shaft 20 connected by a suitable system of levers 21 with a push button 22.

In order to close valve 17 automatically 60 from the tracker board I provide a power pneumatic 25 having a spring finger 26 adapted to engage the valve. I prefer to so arrange finger 26 that it can act upon valve 17 in one direction only, so that said valve 65 may be closed by the lever 19 without affecting the pneumatic 25. The pneumatic 25 communicates, through a passage 27, with a valve chamber 28 which is formed within chamber 12. The valve chamber 28 70 comprises a top board 29 carrying a valve seat having a central opening 30, and a bottom board 31 having an opening 32 in line with the opening 30. The opening 30 communicates with a space 33 which, 75 through tube 34, is in constant and free communication with the atmosphere. Passage 32, however, communicates through space 35 with chamber 12. Mounted in the valve chamber 28 is an ordinary two-faced valve 80 36, one face adapted to seat over opening 30 and the other face adapted to seat over opening 32, the thickness of valve 36 being such, as is common, that the passages 32 and 30 may be alternately opened and closed 85 thereby. Valve 36 carries the usual stem 37 having a head 38 which head lies upon the diaphragm 39 of an ordinary pouch-pneumatic, the chamber 40 of which communicates, through tube 41, with the atmosphere 90 through the intermedium of the tracker board, as will be hereinafter explained. Chamber 40 also communicates, through a small bleeding passage 42, with chamber 12.

One side of chambers 12 and 13 is formed 95 by a removable board 50 which forms the base of the pressure regulator now to be described, said board being held in position by any suitable means, as shown, a suitable packing 51 (see Fig. 2) being provided to insure a 100 suitable air-tight joint. Formed through board 50 is a passage 52 which communicates with chamber 12, and a passage 53 which communicates with chamber 13. Secured to board 50 over passage 52 is a valve box 54 105 having an opening 55 in one side, so that there may be communication between passages 52 and 53 through the opening 55 and

box 54. Opening 55 may be closed more or less by a swinging valve 56 pivoted at one end to box 54 and at the other end connected to the swinging member 57 of a regulator 5 pneumatic R attached to board 50 over box 54 and covering passage 53, a spring 58 being provided to normally distend said pneumatic. An opening 59 is formed through member 57 of a size sufficient to permit said 10 member 57 to fold down closely over box 54 and valve 55 in order that the pneumatic may be as sensitive as possible and have a cubic content as small as possible and, in order to facilitate inspection of valve 56, this opening 59 is closed by a removable board 60, said board being removably held in position by any suitable means.

In order to apply this apparatus to a "divided tracker board" instrument, and 20 designating the solo apparatus by the letter "S", it will be seen, by referring to Fig. 3, that I use two of the solo devices S, one having its passages 14 connected to the wind chest of the bass while the other has its pass 25 sages 14 connected to the wind chest of the treble. The passages 41 of the bass and treble solo devices are connected to ports 71 and 71' respectively, in the tracker board 72. The passages 34 are brought together into a 30 passage 73 which is closed by a slide valve 74 normally held in closing position by a spring 75, the arrangement being such that atmospheric pressure cannot pass into chambers 33 until valve 74 is depressed by the operator.

35 In operation: A music sheet of the ordinary kind, having perforations mating with the usual tracker board openings 72', is also provided with solo perforations adapted to register with the tracker board openings 71 40 and 71'. Whenever the tracker board opening 71 or 71' is closed, the pressure within chamber 40 of the secondary or pouch pneumatic is reduced, by reason of the communication through bleed-hole 42 with chamber 45 12, and consequently pneumatic 25 is distended (if valve 74 is depressed so as to open passages 73—34) so that valve 17 is held over passage 16, and the only communication between the wind chest and the bellows is 50 through chambers 13 of the solo devices, thence through the pressure regulator R, *i. e.*, passages 53, 55 and 52, to chamber 12, and thence through passages 15 to the bellows. Consequently, suction in chamber 12 causes 55 a partial collapse of the regulator pneumatic R until the vacuum produced within chamber 13, and the wind chest, reaches an amount determinable by the strength of spring 58, no matter how hard the bellows, 60 connecting with passage 15, may be worked, this action being an ordinary well known action and resulting in a uniform pressure within the wind chest considerably less in actuating effect than lies within the power of 65 the bellows. As a consequence, the power

pneumatics for the piano action (not shown) will be actuated with a uniform and minimum force so as to produce sounds of minimum intensity. Whenever the tracker board opening 71 or 71' is uncovered, however, atmospheric pressure rushes into chamber 40 of the pouch-pneumatic, or primary pneumatic, and causes said pneumatic to distend so as to lift valve 36 to cover opening 30 and uncover opening 32, thus establishing 70 communication between chamber 12 and the interior of pneumatic 25, through passage 27, whereupon said pneumatic is collapsed so as to permit spring 18 to drive valve 17 away from opening 16, thus establishing 75 direct communication between chamber 13 and chamber 12, whereupon the full force of the bellows may act upon the power pneumatics connected with the said chamber 13, thus causing a maximum actuation of 80 the particular sound-producing pneumatics which may at that moment be designated by the particular portion of the perforated music sheet then passing over the tracker board. As soon as opening 71 or 71' is closed, 85 by the passage of the music sheet, the pressure within chamber 40 is diminished through bleed-hole 42 and valve 36 returns to normal position so that pneumatic 25 will be again distended by an in-rush of atmospheric pressure through passages 34, 30 and 27, and valve 17 will be thrown over opening 16, whereupon succeeding portions of the music sheet will cause an actuation of the sound-producing devices through the regulators R. 90

If the operator desires to suppress the solo effects in either bass or treble, he has merely to depress the proper button 22 so as to hold the valve 17, of the corresponding solo device, closed; this action not interfering in 105 the least with the automatic actuation of the other solo device from the tracker board.

If the automatic solo effects are not desired, the operator will leave push button 74 undisturbed, so that passages 34 will be 110 closed by valve 74 and consequently the opening and closing of port 71 or 71' will have no effect upon pneumatics 25 and consequently no effect upon valves 17 because no communication with atmospheric pressure can 115 be had for chambers 33.

The apparatus is also under the control of the operator, manually, by means of the two buttons 22 which may be manipulated in order to manually close the valves 17 and, 120 by skilful manipulation, may produce the same results accomplishable automatically by the tracker board connection.

I claim as my invention:

1. A solo device for automatic players 125 comprising a pair of main chambers with a passage forming a direct communication between said chambers, a valve adapted to close said passage, a pressure regulator also forming a communication between the two 130

chambers, and a valve-operating pneumatic action mounted in one of said chambers to operate said valve, said valve-operating pneumatic action comprising a power-pneumatic 5 engaging the valve, a main valve chamber communicating with said power-pneumatic and communicating on one side with atmosphere and on the other side with the chamber within which the structure is mounted, a main-valve mounted within said main-valve chamber and adapted to automatically 10 control said communications, a primary-pneumatic for operating said main-valve, a tracker board, and a communication between said tracker board and said primary-pneumatic.

2. A solo device for automatic players comprising a pair of main chambers with a passage forming a direct communication between said chambers, a valve adapted to close said passage, a pressure regulator also forming a communication between the two chambers, and a valve-operating pneumatic train mounted in one of said chambers to operate said valve, said valve-operating pneumatic train comprising a power-pneumatic 20 engaging the valve, a main valve chamber communicating with said power-pneumatic and communicating on one side with atmosphere and on the other side with the chamber within which the structure is mounted, a main-valve mounted within said main-valve chamber and adapted to automatically control said communications, a primary-pneumatic for operating said main-valve, a tracker board, and a communication between 25 said tracker board and said primary-pneumatic.

30 3. A solo device for automatic players comprising a pair of main chambers with a passage forming a direct communication between said chambers, a valve adapted to close said passage, a pressure regulator also forming a communication between the two chambers, and a valve-operating pneumatic train mounted in one of said chambers to operate said valve, said valve-operating pneumatic train comprising a power-pneumatic 35 engaging the valve, a main valve chamber communicating with said power-pneumatic and communicating on one side with atmosphere and on the other side with the chamber within which the structure is mounted, a main-valve mounted within said main-valve chamber and adapted to automatically control said communications, a primary-pneumatic for operating said main-valve, a tracker board, a communication between 40 said tracker board and said primary-pneumatic, and means for controlling admission to the atmospheric side of the main valve chamber.

4. A solo device for automatic players comprising a pair of main chambers with a passage forming a direct communication between said chambers, a valve adapted to close said passage, a pressure regulator also forming a communication between the two chambers, and a valve-operating pneumatic train mounted in one of said chambers to operate said valve, said valve-operating pneumatic train comprising a power-pneumatic 50 engaging the valve, a main valve chamber communicating with said power-pneumatic and communicating on one side with atmosphere and on the other side with the chamber within which the structure is mounted, a main-valve mounted within said main-valve chamber and adapted to automatically control said communications, a primary-pneumatic for operating said main-valve, a tracker board, a communication between 55 said tracker board and said primary-pneumatic, and means independent of the tracker board for controlling admission to the atmospheric side of the main valve 60 chamber.

4. A solo device for automatic players comprising a pair of main chambers with a passage forming a direct communication between said chambers, a valve adapted to close said passage, a pressure regulator also 70 forming a communication between the two chambers, and a valve-operating pneumatic train mounted in one of said chambers to operate said valve, said valve-operating pneumatic train comprising a power-pneumatic 75 engaging the valve, a main valve chamber communicating with said power-pneumatic and communicating on one side with atmosphere and on the other side with the chamber within which the structure is mounted, a main-valve mounted within said main valve chamber and adapted to automatically control said communications, a primary-pneumatic for operating said main-valve, a tracker board, and a communication between 80 said tracker board and said primary-pneumatic.

5. A solo device for automatic players comprising a pair of main chambers with a passage forming a direct communication between 90 said chambers, a valve adapted to close said passage, a pressure regulator also forming a communication between the two chambers, and a valve-operating pneumatic train mounted in one of said chambers to operate said valve, said valve-operating pneumatic train comprising a power-pneumatic 95 engaging the valve, a main valve chamber communicating with said power-pneumatic and communicating on one side with atmosphere and on the other side with the chamber within which the structure is mounted, a main-valve mounted within said main valve chamber and adapted to automatically control said communications, a primary-pneumatic for operating said main-valve, a tracker board, a communication between 100 said tracker board and said primary-pneumatic, and means for controlling admission to the atmospheric side of the main valve 105 chamber.

6. A solo device for automatic players comprising a pair of main chambers with a passage forming a direct communication between said chambers, a valve adapted to close said passage, a pressure regulator also forming a communication between the two chambers, and a valve-operating pneumatic train mounted in one of said chambers to operate said valve, said valve-operating pneumatic train comprising a power-pneumatic 115 engaging the valve, a main valve-chamber communicating with said power-pneumatic and communicating on one side with atmosphere and on the other side with the chamber 120 within which the structure is mounted, a main-valve mounted within said main valve chamber and adapted to automatically control said communications, a primary-pneumatic for operating said main-valve, a 125

tracker board, a communication between said tracker board and said primary-pneumatic, and means independent of the tracker board for controlling admission to the atmospheric side of the main valve chamber.

In witness whereof, I have hereunto set my hand and seal at Richmond, Indiana,

this tenth day of July, A. D. one thousand nine hundred and seven.

FRANCIS W. DRAPER. [L. S.]
